UNITED STATES PATENT OFFICE.

JACOB UNGERER, OF NEWARK, NEW JERSEY.

CIGAR-PIERCING DEVICE.

SPECIFICATION forming part of Letters Patent No. 297,956, dated April 29, 1884.

Application filed September 17, 1883. (No model.)

To all whom it may concern:

Be it known that I, JACOB UNGERER, a citizen of the United States, residing at Newark, in the county of Essex and State of New Jersey, have invented certain new and useful Improvements in Devices for Piercing Cigars; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide more perfect means for piercing cigars, so that the smoke may be drawn therethrough with greater ease than when pierced with a simple needle, said needle tending to close the pores of the cigar, and without breaking or cutting the cigar to such an extent as to cause the tobacco thereof to be drawn into the mouth when smoking, as is now the case when the end of the cigar is cut off by the ordinary cutters.

The invention consists in the arrangement and combination of parts, substantially as will be hereinafter set forth; and finally embodied in the claim.

Referring to the accompanying drawings, in which similar letters of reference indicate like parts in the figures, Figure 1 is an enlarged longitudinal sectional view of my combined piercing device and watch-chain bar, and Fig. 2 is an elevation of the same.

In carrying out the invention I form a watch-chain bar with a ring secured thereto, adapted to link with the watch-chain, said bar being formed of a slotted tube, *a*. Within said tube I secure a longitudinal and stationary bar, *b*, around which is arranged a sliding tubular

40 cutter, *c*, capable of cutting a hole into the cigar and withdrawing the tobacco therefrom. Said tubular cutter is connected with a finger-piece, *d*, which in the case shown is a sliding collar working on the tubular case *a*, a slot in said case limiting the action of the finger-piece. 45 By projecting the tubular cutter forward and thrusting the same into the cigar a hole is made therein, the tobacco from which lodges in the interior of the said cutter. When the latter is again drawn back into its receptacle 50 over the central bar, said bar clears the said tube of the tobacco lodged therein preparatory to a subsequent piercing process.

I do not wish to be understood as limiting myself to the exact shape of the tubular cutter, as the same may be other than round, nor to the exact arrangement of parts herein shown; and, further, instead of adapting the piercer to be also employed as a watch-chain bar, as shown, it may be connected with a knife or 60 any other article suitable to be carried around or upon the person.

Having thus described my invention, what I claim as new is—

The combination of the case, a center bar 6 arranged therein and fixed in its relation thereto, a sliding tubular cutter working between the bar and case, and a finger-piece arranged outside the case and connected to the cutter, substantially as set forth.

In testimony that I claim the foregoing I have hereunto set my hand this 7th day of September, 1883.

JACOB UNGERER.
